ALBERT B. PEDERSEN, OF SALT LAKE CITY, UTAH.

CURLING IRON.

Application filed February 9, 1926. Serial No. 87,126.

My invention relates to improvements in curling irons, and it consists in the combinations, constructions and arrangements herein described and claimed.

- 5 An object of the invention is the provision of a curling iron which includes two cooperative jaw members, one of which is adapted to move toward and away from the other jaw member while remaining substantially parallel with the second jaw member, whereby a relatively great number of hairs or strands of hair can be gripped uniformly between the jaw members and thus crimped uniformly.
- 15 A further object of the invention is the provision of a curling iron of the character described which includes two cooperative elongated crimping jaws or members which will be maintained substantially parallel with each other at all times and which also includes simple and conveniently and easily operable means for opening said jaw members when desired.

25 Other objects and advantages of the invention will be apparent from the following description, considered in conjunction with the accompanying drawings, in which—

Figure 1 is a side elevation of the improved curling iron, showing the jaws closed,

Figure 2 is a view partly in side elevation and partly in vertical section, showing the jaws open,

Figure 3 is a perspective view of the movable jaw member,

Figure 4 is a sectional view substantially along the line 4—4 of Figure 1.

The improved curling iron comprises two cooperative elongated jaws 1 and 2, respectively. The jaw 1 may be a straight rod-like member, as shown, made of a suitable metal, having an integral shank portion 3 which is curved reversely along arcs struck by radii of relatively great length, the rear end portion of the shank 3 being connected in any suitable known manner, as by means of the ferrule 4 with a handle 5. The handle 5 preferably is of wood or any other suitable heat insulating material. The arrangement is such that the handle 5 will lie in a plane which extends obliquely to the plane of the jaw 1.

50 The jaw 2 is arcuate in cross sectional contour and is adapted to overlap and partially receive the jaw 1 when the jaws 1 and 2 are in closed position as shown in Figure

1. The jaw 2 also is made of a suitable metal. The jaw 2 is formed with integral parallel extensions or arms 6 on the sides of the jaw 2 at the rear end of the latter. 60 The arms 6 straddle the rearward end portion of the jaw 1 and extend substantially at right angles to the direction of length of the jaw 1. These arms 6 are formed with aligned elongated slots 7 which extend longitudinally of the arms 6. The slots 7 constitute guide slots through which oppositely extending aligned guiding and retaining studs or projections 8 on the rearward end portion of the jaw 1 extend, the slotted portions of the arms 6 being in sliding contact with the projections 8. The outer ends of the projections 8 preferably are upset as shown to prevent any appreciable lateral play of the jaw 1 between the arms 6 when the jaws 1 and 2 are open without such pressure of the arms on the jaw 1 as might cause considerable friction or retard the movements of the jaw 2 between closed position as shown in Figure 1 and open position as 80 shown in Figure 2. The projections 8 may be the extending ends of a pin which extends transversely through the rearward end portion of the jaw 1 as shown in Figure 4.

85 The means for opening the jaws includes a lever 9 which preferably is of sheet metal construction and which is bifurcated from its forward end for approximately half its length, thus producing a pair of forks 10 which straddle the shank 3 and have the forward end portions thereof disposed in straddling relation to the end portions of the arms 6.

90 A transverse pivot element 11 connects the lapped end portions of the forks 10 and the arms 6. The forks 10 are enlarged edge-wise at the rearward ends to produce a pair of ears 12 which straddle the shank 3 intermediate the length of the latter and to which the shank 3 is attached by means of a transverse pivot element 13 which thus constitutes a fulcrum for the lever 9. The rearward end portion of the lever 9 carries a finger piece or button 14 which is secured to the lever 9 in any suitable known manner, as by means of the rivet 15, this button being disposed at the side of the lever 9 which is remote from the handle 5.

100 The portion of the pivot element 11 which extends between the arms 6 carries a sleeve or roller 16 against which an end portion

of a spring bar 17 presses. The rearward end portion of the spring bar 17 is secured, as at 18, to the shank 3 and the forward end portion of the spring bar 17 extends between the sleeve or roller 16 and the rearward end portion of the jaw 1.

From the foregoing description of the various parts of the device, the operation thereof may be readily understood. The 10 spring bar 17 exerts pressure on the roller 16, tending to resist movement of the arms 6 and therefore the jaw 2 from the position shown in Figure 1 to the position shown in Figure 2. When it is desired to move the 15 jaw 2 from the position shown in Figure 1 to the position shown in Figure 2, the finger or fingers of a hand in which the handle 5 is held are extended over the rearward end portion of the lever 9 against the button 14 20 and the rearward end portion of the lever 9 is swung toward the handle 5, thereby swinging the forward end portion of the lever toward the jaw 1 against the action of the spring 17 and moving the jaw 2 away from the jaw 1.

This movement of the jaw 2 relatively to the jaw 1 will be guided because of the engagement of the studs or projections 8 with the guide slots 7 and the jaw 2 will remain 30 substantially parallel to the jaw 1 at all times. The pressure which the spring 17 exerts on the roller 16 will be increased as the jaw 2 moves from the position shown in Figure 1 toward the position shown in Figure 2 and when the grip on the rearward end portion of the lever 9 is relaxed, the spring 15 will function to return the jaw 2 to closed position, as shown in Figure 1.

Obviously, my invention is susceptible of 40 embodiment in forms other than that which is illustrated in the accompanying drawing and I therefore consider as my own all such modifications and adaptations of the form thereof herein described as fairly fall within the scope of the appended claims.

I claim:—

1. A curling iron comprising a pair of cooperative elongated jaws, a curved shank rigid with one of said jaws at the rearward 50 end of the latter, a handle rigid with said shank, the axial line of said handle extending obliquely to the axial line of said one jaw, a pair of arms extending from the rearward end portion of said other jaw in straddling relation to said first jaw, a lever fulcrumed intermediate its length on said shank and pivotally attached at its forward end to the arms on the second jaw, and guide means for maintaining said second jaw substantially parallel to said first jaw while permitting bodily movement of said second jaw relatively to the first jaw.

2. A curling iron comprising a pair of cooperative elongated jaws, a curved shank rigid with one of said jaws at the rearward 60

end of the latter, a handle rigid with said shank, the axial line of said handle extending obliquely to the axial line of said one jaw, a pair of arms extending from the rearward end portion of said other jaw in straddling relation to said first jaw, a lever fulcrumed intermediate its length on said shank and pivotally attached at its forward end to the arms on the second jaw, guide means for maintaining said second jaw substantially parallel to said first jaw while permitting bodily movement of said second jaw relatively to the first jaw, spring means resisting movement of said movable jaw away from said other jaw and tending to return said movable jaw toward said other jaw, and a button on the rearward end portion of said lever, said button constituting a finger grip member.

3. A curling iron comprising an elongated stationary jaw of rod-like form, a shank integral with said jaw at the rearward end of the latter, said shank being curved reversely along arcs struck by radii of relatively great length, a handle secured on the rearward end portion of said shank, the axial line of said handle extending obliquely to the direction of length of said stationary jaw, a movable elongated jaw of arcuate cross sectional configuration and adapted to overlap and partially receive said stationary jaw, the sides of said movable jaw having extensions constituting arms straddling the rearward end portion of said stationary jaw, said arms extending substantially at right angles to the direction of length of the movable jaw, said arms having aligned slots extending longitudinally thereof, oppositely extending projections on the rearward end portion of said stationary jaw extending slidably through said slot, a lever having forks straddling said shanks, the end portions of said forks straddling the end portions of said arms, a transverse pivot element connecting the lapped portions of said forks and said arms, a transverse pivot element connecting the rearward end portions of said forks with said shanks, and an elongated spring member having the rearward end portions thereof secured to said shanks and extending between said first named pivot element and said stationary jaw and exerting pressure on said first named pivot element, tending to resist movement of said movable jaw away from said stationary jaw.

4. A curling iron comprising an elongated stationary jaw of rod-like form, a shank integral with said jaw at the rearward end of the latter, said shank being curved reversely along arcs struck by radii of relatively great length, a handle secured on the rearward end portion of said shank, the axial line of said handle extending obliquely to the direction of length of said stationary jaw, a movable elongated jaw of arcuate

cross sectional configuration and adapted to overlap and partially receive said stationary jaw, the sides of said movable jaw having extensions constituting arms straddling the rearward end portion of said stationary jaw, said arms extending substantially at right angles to the direction of length of the movable jaw, said arms having aligned slots extending longitudinally thereof, oppositely extending projections on the rearward end portion of said stationary jaw extending slidably through said slot, a lever having forks straddling said shanks, the end portions of said forks straddling the end portions of said arms, a transverse pivot element connecting the lapped portions of said forks and said arms, a transverse pivot element connecting the rearward end portions of said forks with said shanks, and an elongated spring member having the rearward end portions thereof secured to said shanks and extending between said first named pivot element and said stationary jaw and exerting pressure on said first named pivot element,

tending to resist movement of said movable jaw away from said stationary jaw, and a roller on said first named pivot element against which the forward end portion of said spring member bears.

5. A curling iron comprising a jaw of rod-like form, a shank rigid with said jaw at the rearward end of the latter, a second jaw for cooperating with said first named jaw, the rearward end portion of said second jaw having spaced extensions constituting arms straddling the rearward end portion of the first jaw, said arms extending substantially at right angles to the direction of length of the second named jaw, a lever fulcrumed intermediate its length on said shank and pivotally attached at its forward end to the arms of the second jaw, and guide means for maintaining said second jaw substantially parallel to said first jaw while permitting bodily movement of said second jaw relatively to the first jaw.

ALBERT B. PEDERSEN.
